INSECTICIDAL COMPOSITION

**Vernon E. Haury, El Cerrito, Calif., assignor to
Shell Development Company, San Francisco,
Calif., a corporation of Delaware**

**No Drawing. Application July 17, 1944,
Serial No. 545,400**

13 Claims. (Cl. 167—24)

1

This invention relates to new and novel compounds which are particularly suitable for killing noxious insects and the like. More specifically, the invention is concerned with insecticidal compositions containing N-cyclo-substituted cyclo-olefinic imines having the imino nitrogen linked between two ring carbon atoms.

Among the best known toxicants used in insecticidal compositions, particularly in household insecticides, are pyrethrum and rotenone. These are both derived from plants grown in foreign countries and are therefore expensive and not always obtainable in desired quantities. Thus, many organic compounds which are more readily available in this country have been proposed as toxicants for insecticidal compositions. However, although many of these proposed compounds are relatively efficient for momentarily incapacitating insects, they are relatively inefficient for killing insects. In addition to the desirability of high toxic action, for use in insecticides, particularly in household insecticides, the compounds must be light-stable, compatible with light paraffinic mineral oils, such as kerosene, and free from injurious effect and offensive odor to human beings and tendency to stain walls, fabrics, etc.

It is an object of the present invention to provide an insecticidal composition which is highly toxic to insects but of low toxicity to man and other warm-blooded animals. Another object is to provide new insecticidal compositions which can be prepared from readily available domestic and inexpensive materials. A further object is to provide an improved insecticidal composition containing a fast-acting synthetic toxicant which is stable toward light. A further object of this invention is to provide an activator for toxic plant extracts, such as pyrethrum and derris resin or rotenone in insecticidal compositions.

We have found that N-cyclo-substituted cyclo-olefinic imines having the imino nitrogen atom linked between two ring carbon atoms are particularly effective and highly active insecticidal agents. These compounds may be represented by the general formula:

wherein R_1C represents a cyclo-olefinic radical, which is preferably alkylated with other lower alkyl groups, especially at the 3,5 positions and particularly dialkylated at the same ring carbon, and R_2 as a cyclic radical, which may be alicyclic, either saturated or olefinic, aromatic, or heterocyclic. Thus, for example R_1C may be cyclopentenyl, methylcyclopentyls, amyl cyclo-

2

pentenyls, cyclohexenyl, dimethyl cyclohexenyls, allyl cyclohexenyls, vinyl cyclohexenyls, methyl allyl cyclohexenyls, trimethyl cyclohexenyls, such as 3,3,5-trimethyl-3-cyclohexenyl (i. e. isophoronyl), cyclohexadienyl, methylcyclohexadienyl, cycloheptenyl, etc. R₂ may also be a cyclo-olefinic group such as the above, or preferably, a saturated cyclic radical, such as cyclopentyl, ethyl cyclopentyls, methallyl cyclopentyls, methyl butyl cyclopentyls, cyclohexyl, allyl cyclohexyls, diallylcyclohexyls, isopropyl cyclohexyls, secondary butyl cyclohexyls, dimethyl cyclohexyls, trimethylcyclohexyls, such as 3,3,5-trimethylcyclohexyl, 4-isobutyl cyclohexyl, endomethylene cyclohexyls, etc., or less preferably aromatic groups, such as, for example, phenyl, methallyl phenyl, tolyl, xylyl, vinyl phenyl, butyl phenyls, 4-isobutyl phenyl, naphthyl, methyl naphthyl, crotonyl naphthyl, triallyl naphthyl, anthryl, etc., or heterocyclic radicals, such as pyridyl, sulfolanyl, methyl sulfolanyl, pyrrolyl, thioenyl, furyl, butyl carbothionyl, octyl carbothionyl, etc. In general, there may be included in the rings, for example, such atoms or groups as

Also, N-cyclo-substituted cyclo-olefinic imines 30 may be used, which also have in the molecule one or more of the following groups: sulfo, amino, hydroxy carboxy, amido, mercapto, keto, ether, ester, lactone, lactam, ketal, acetal, halogen, halo-hydrin, epoxide, cyanohydrin, azo, diazo, thiazo, 35 oxazo, thioether, thioimino, cyano, thiocyanato, etc.

The preferred compound of the present class of compounds is N-(3,3,5-trimethylcyclohexyl) isophoronimine, which may also be named N-(3,3,5-trimethylcyclohexyl)-3,3,5-trimethyl-2-cyclohexen-1-imine.

The present imines may be prepared in any suitable manner, such as by catalytic dehydrogenation of the proper secondary amines, as disclosed in my copending application Serial No. 45 529,873, filed April 5, 1944. Therein, the desired imines are produced by contacting a secondary amine, wherein the —NH— group is directly linked to two carbon atoms at least one of which is directly linked to a hydrogen atom, with a 50 dehydrogenation catalyst at a dehydrogenation temperature, i. e., a temperature sufficiently elevated to effect the removal of a hydrogen atom from the said hydrogen-bearing carbon atom and another hydrogen atom from the contiguous nitrogen atom, thereby causing the formation of a 55

carbon-nitrogen double bond. Thus, for example, N-(3,3,5-trimethylcyclohexyl) isophorona-mine is converted to N-(3,3,5-trimethylcyclohexyl) isophoroni-mine by contacting said secondary amine with a dehydrogenation catalyst, e. g., an active nickel catalyst, at a temperature of between 100° C. and about 500° C.

The N-cyclo-substituted cyclo-olefinic imines, either alone or in combination with other active or inactive substances, may be applied to plants, animals, fabrics and the like, by spraying, dusting, pouring, dipping, etc., in the form of concentrated liquids, solutions, suspensions, dusting powders, and the like, containing such concentration of the active principle as is most suited for the particular purpose at hand. They may be applied, for example, in the form of dilute solutions, in a suitable solvent or mixture of solvents, containing, for instance, petroleum distillate, lignite tar oils, paraffin oils, naphthenes, chlorinated hydrocarbons, such as dichloropropane, chlorinated ethers, ketones, such as acetone, fenchyl and bornyl alcohols, mono- and poly-hydric alcohols, glycol ethers, or the like or mixtures thereof.

The present compounds may be advantageously used in combination with other insecticides or fungicides such as pyrethrum, derris resins, rotenone, nicotine, lime-sulphur, Bordeaux mixture, copper sulfate, copper carbonates, sulphur, mercury compounds, sodium, calcium and lead arsenates, iron sulfate, phenol, paradichlorobenzene, unsaturated chlorides, higher unsaturated amides, alkene sulfides, alkyl dithiocarbamates, thiuram sulfides, thiocyanates, thiocyanato esters,

When solutions of the N-cyclo-substituted cyclo-olefinic imine in odorless base kerosene are placed on filter paper and exposed to air, the liquid evaporates leaving substantially no stain behind, which feature is of particular advantage in household insecticides.

The present compounds may also be mixed with or absorbed by finely divided solid materials, such as wood flour, talc, clay, bentonite, sulphur, and carbon black, and used as dusting insecticides.

Modified Peet-Grady tests were made with the N-cyclo-substituted cyclo-olefinic imine of the present invention. The general test is fully described in the 1940 "Blue Book," published by the publisher of "Soap and Sanitary Chemicals" periodical, on pages 193 to 197, as the large group method. Briefly, the test as practiced consists of releasing 100 to 150 flies in an air-conditioned case 6 x 6 x 6 feet and spraying them with 6 ml. of insecticide. After 10 minutes exposure the number of flies which are incapacitated or "knocked down" is noted and all flies transferred to a cage and allowed to recuperate in fresh air for 24 hours, when the dead flies are counted. For the purpose of this study the percentages knocked down at 10 minutes and killed at 24 hours were recorded, as well as the official Peet-Grady numerical rating. The results obtained by testing in the above manner N-(3,3,5-trimethylcyclohexyl) isophoroni-mine in highly refined, odorless kerosene with and without added pyrethrum and, for comparison, a closely related but much less effective compound in said kerosene are given in the following table:

Test No.	5% by vol. of Agent	Per cent by vol. of Pyrethrum Extract	Per cent 10 min. knockdown	Per cent 24 hour kill	Numerical rating ¹
1.....	Di-(3,3,5-trimethylcyclohexyl) amine.....	0	47	14	-23
2.....	N-(3,3,5-trimethylcyclohexyl) isophoroni-mine.....	0	95	53	+16
3.....	N-(3,3,5-trimethylcyclohexyl) isophoroni-mine.....	5	95	79	+35

¹ The numerical rating is calculated as the difference in the percent 24 hour kill from that obtained with an odorless kerosene solution of 5% by vol. of 20:1 pyrethrum extract concentrate.

isothiocyanates, ethylene glycol ether of pinene, butyl mesityl oxide oxalate, polyhalogenated compounds, such as 1,1-diparachlorophenyl 2,2,2-trichloroethane, unsaturated cyclic ketols, such as di-isophrone and its homologues, obtained by condensation of lower ketones, such as acetone, methyl ethyl ketone, etc., according to U. S. Patent 2,307,482, and the like.

As will be readily apparent, the most desirable N-cyclo-substituted cyclo-olefinic imine and solvent, or solvent mixture, or combination with other active and inactive ingredients, will depend considerably upon the particular use for which the material is intended.

For use in household insecticides, N-cyclo-substituted cyclo-olefinic imine is preferably dissolved in a light hydrocarbon oil such as highly refined, odorless kerosene or kerosene distillate with or without the addition of other insecticides and sprays. Ordinarily from about 1% to 25% and preferably from 2% to 8% of the present toxicants are used in such sprays.

For use in sprays, such as horticultural spray oils, there may be added emulsifying agents, such as partial esters of polyhydric alcohols, e. g. glycerol mono-oleate, polyethylene glycol mono laurate, palmitate, stearate, oleate, etc., various soaps, alkali metal salts of sulfuric acid mono esters and organic sulfuric acids and the like.

Besides the control of houseflies (*Musca domestica*), the compositions containing the present N-cyclo-substituted cyclo-olefinic imines may be used for eradicating or controlling various pests, such as insects, e. g., aphids, diabrotica, red spiders, thrips, etc., bacteria and fungi, such as *Aspergillus*, *Penicillium*, *Scherobium rolsit*, etc., and the like.

55 I claim as my invention:

1. An insecticidal composition comprising a carrier and toxic agent having the general formula $R_1C=N-R_2$, wherein R_1C represents an olefinic alicyclic radical, and R_2 is a cyclic radical selected from the group consisting of alicyclic, aromatic, and heterocyclic radicals.

2. An insecticidal composition comprising a carrier and toxic agent having the general formula $R_1C=N-R_2$, wherein R_1C represents an olefinic alicyclic radical, and R_2 is an alicyclic radical.

3. The process of eradicating insects, bacteria, and fungi comprising the step of exposing them to a toxic agent having the general formula $R_1C=N-R_2$, wherein R_1C represents an olefinic alicyclic radical, and R_2 is a cyclic radical selected from the group consisting of alicyclic, aromatic, and heterocyclic radicals.

4. An insecticidal composition comprising a carrier and a toxic agent having the general formula $R_1C=N-R_2$, wherein R_1C represents an ole-

finic alicyclic radical, and R_2 is an alkylated alicyclic radical.

5. An insecticidal composition comprising a carrier and toxic agent having the general formula $R_1C=N-R_2$, wherein R_1C represents an alkylated olefinic alicyclic radical, and R_2 is a carbocyclic radical.

6. An insecticidal composition comprising a carrier and toxic agent having the general formula $R_1C=N-R_2$, wherein R_1C represents an alkylated alicyclo-olefinic radical, and R_2 is an alkylated alicyclic radical.

7. An insecticidal composition comprising a carrier and a polyalkylated cyclohexenyl imine wherein the imino nitrogen atom is directly attached to the ring of an alkylated alicyclic radical and has the imino nitrogen atom linked between two ring carbon atoms.

8. An insecticidal composition comprising a carrier and a 3,3,5-trimethyl cyclohexenyl imine wherein the imino nitrogen atom is directly attached to the ring of an alkylated alicyclic radical and has the imino nitrogen atom linked between two ring carbon atoms.

9. An insecticidal composition comprising an insecticidal plant extract and a toxic agent having the general formula $R_1C=N-R_2$, wherein R_1C represents an olefinic alicyclic radical, and R_2 is a cyclic radical selected from the group consisting of alicyclic, aromatic, and heterocyclic radicals.

10. An insecticidal composition comprising pyrethrum and an N-cyclo-substituted cyclo-ole-

finic imine having the imino nitrogen atom linked between two ring carbon atoms.

11. A plant spray insecticide comprising a mineral spray oil, an emulsifying agent and a toxic agent having the general formula $R_1C=N-R_2$, wherein R_1C represents an olefinic alicyclic radical, and R_2 is a cyclic radical selected from the group consisting of alicyclic, aromatic, and heterocyclic radicals.

12. A household insecticide comprising a light hydrocarbon oil and N-(3,3,5-trimethylcyclohexyl) 3,3,5-trimethyl-2-cyclohexen-1-onimine.

13. An insecticidal composition comprising a liquid hydrocarbon and toxic agent having the general formula $R_1C=N-R_2$, wherein R_1C represents an olefinic alicyclic radical, and R_2 is a cyclic radical selected from the group consisting of alicyclic, aromatic, and heterocyclic radicals.
